OUTDOOR STOVE FOR RECREATION AREAS

Wells S. Bearinger, St. Ann, Mo., assignor to
Empire Stove Company, Belleville, Ill.

Filed Feb. 20, 1970, Ser. No. 21,544

Term of patent 14 years

Int. Cl. D7—02

U.S. Cl. D81—10

FIG. 1

FIG. 4

FIG. 2

FIG. 3

FIG. 1 is a perspective view of an outdoor stove for recreation areas;

FIG. 2 is a front elevational view of the stove;

FIG. 3 is an elevational view of the left side of the stove; and

FIG. 4 is a top plan view of the stove.

The right side of the stove, other than being a reversal of the left side, is the same as the left side. The back of the stove is flat.

I claim:

The ornamental design for an outdoor stove for recreation areas, substantially as shown and described.
